UNITED STATES PATENT OFFICE.

JOHN G. WALLACE, OF CINCINNATI, OHIO.

DESIGN FOR A BOW.

Specification forming part of Design No. 5,751, dated April 2, 1872.

Specification of a new and original Design for a Lady's Bow, invented by JOHN G. WALLACE, of Cincinnati, in the county of Hamilton and State of Ohio.

My design consists essentially of a bow, upon which is secured a number of "spots" or disks, that are arranged in any desired manner to suit the taste.

A represents the bow proper, which is composed of Mechlin net or any other suitable reticulated stuff, and said bow has stitched, glued, or otherwise attached to it a number of "spots" or disks, B. These "spots" may be made of velvet or any other appropriate material, and of various colors.

The spots, being of a different material and color to that of the bow proper, add greatly to the attractiveness of the article.

I do not propose to confine myself to the identical shape or style of bow herein represented, as it is evident that the same may be varied to suit the changes of fashion; the main feature of the design being the employment of the spots, substantially as shown.

Claim.

I claim as my invention—
The design for a bow, substantially as shown.
In testimony of which invention I hereunto set my hand.

JOHN G. WALLACE.
